(57) **CLAIM**

The ornamental design for a fruit bowl, as shown and described.

DESCRIPTION

FIG. 1 is a perspective view of a fruit bowl showing my new design;

FIG. 2 is a front view of the fruit bowl;

FIG. 3 is a right side view of the fruit bowl;

FIG. 4 is a rear side view of the fruit bowl;

FIG. 5 is a left side view of the fruit bowl;

FIG. 6 is a top view of the fruit bowl;

FIG. 7 is a bottom view of the fruit bowl; and

FIG. 8 is a perspective view of a second embodiment of a fruit bowl showing my new design, which is the same as the first embodiment except for the wire shape; and,

FIG. 9 is a cross sectional view of the wire used to form the fruit bowl, taken along line 9-9 of FIG. 2.

The broken lines in the drawing illustrate environmental matter and form no part of the claimed design.
